PRIMER FOR AMMUNITION

George H. Jacobs, Kings Mills, Ohio, assignor, by
mesne assignments, to The Peters Cartridge
Company, a corporation of Delaware.

No Drawing. Application October 7, 1931,
Serial No. 567,525

4 Claims. (Cl. 52-2)

This invention relates to improvements in priming mixtures which are disclosed herein particularly in relation to their uses and advantages in small arms ammunition.

At present there are two well-known types of small arms primers, namely, center fire and rim fire primers. A center fire primer is composed of a brass, copper or gilding metal cup into which is loaded under pressure the explosive compound which is cemented or held in place by gum, collodion, or some other adhesive, or it may be covered by a paper or tinfoil disc which is held in place by a similar adhesive. The rim fire primers are contained in the head of the cartridge case within the annular rim or cavity provided for this purpose. The priming composition is introduced by means of centrifugal force, and projected outwardly from the center into the cavity. It is held in place by gum, collodion, or some suitable adhesive.

The priming mixtures in general use comprise a detonating agent, a fuel and an oxidizing agent. The properties of these three classes of bodies and their proportions must be adjusted in relation to the arms in which the ammunition is to be used, and in relation to the propellant powder used in the ammunition to the end that the priming mixture be appropriately sensitive to the action of the firing pins in existing arms and that the most efficient propellant powders be appropriately ignited by the priming mixture.

This invention comprises in its broader aspect, providing a fuel component of the priming mixture which produces a heat of combustion and maximum temperature of explosion of the priming mixture sufficiently high in value to ignite efficiently all types of propellant powders.

The invention is also directed to a fuel component of the priming mixture which provides said requisite heat of combustion and maximum temperature of explosion when used in combination with special oxidizing agents which do not cause rusting or corrosion of the barrel of the fire arm in which the ammunition is used. These oxidizing agents which are adapted to inhibit rather than accelerate corrosion of the barrel of the fire arm, usually comprise nitrates and chromates.

While the new fuel of this invention is adapted to provide the desired thermal properties discussed above, it is particularly and peculiarly adapted to cooperate with the rustless oxidizing agents to provide the desired thermal conditions

without detracting from the rustless characteristics of the oxidizing agents.

The new fuel element of this invention is exemplified by metallic zirconium.

In carrying out my invention as a priming mixture for rim fire cartridges, I may use substantially the following:

	Per cent
Fulminate of mercury	30-50
Barium nitrate	10-30
Lead chromate	2-20
Lead sulphocyanate	3-15
Ground glass	15-35
Zirconium	2-20

In carrying out my invention as a priming mixture for center fire cartridges, I may use substantially the following:

	Per cent
Fulminate of mercury	20-40
Barium nitrate	25-45
Lead chromate	2-15
Lead sulphocyanate	5-25
Zirconium	2-30

These proportions, however, may be varied so as to meet the requirements of the different propellant powders and different caliber cartridges.

In proceeding to make my improved priming mixture the barium nitrate, lead chromate, lead sulphocyanate and ground glass are weighed out, 30 screened and mixed dry. The zirconium either in a dampened or dry state is then weighed out and mixed in the above mixture. The fulminate in a dampened state is then weighed out and added, together with a small quantity of a gum solution, to the mixture and the whole thoroughly mixed until the ingredients are evenly distributed. The mixture is then ready for use in the manufacture of center fire primers or primed rim fire cartridge shells.

I also find that I may use other detonating agents such as lead trinitroresorcinate, or lead azide in place of the mercury fulminate. Also I may substitute lead nitrate, basic lead nitrate, strontium nitrate, or lead peroxide in place of the barium nitrate or lead chromate. Also I may substitute other fuel agents such as antimony sulfide, calcium silicide, ferro-silicon, potassium picrate, trinitroresorcinate, pentaerythritetetronitrate, and guanyl nitrosoaminoguanyltetracene in place of the lead thiocyanate. Also I may use granulated witherite (natural barium carbonate) in place of the ground glass as an abrasive agent. Such substitutions in whole or in part fall within the scope of my invention.

The most important ingredient in my improved rustless priming mixture is embodied in the use of powdered metallic zirconium. The heat of combustion of zirconium is 1957 calories per gram which is greatly in excess of any ingredient heretofore used in priming mixtures. Zirconium is also extremely stable when stored under high heat and humidity conditions and the products of combustion, when zirconium is burned, will not cause rust or corrosion of the barrel of the firearm in which it is used.

Having described my invention, I desire to be limited only by the ensuing claims:

1. A non-corrosive priming mixture comprising fulminate of mercury, barium nitrate, lead

chromate, lead sulphocyanate, and powdered metallic zirconium.

2. A non-corrosive priming mixture containing 20% to 50% fulminate of mercury, 10% to 45% barium nitrate, 2% to 20% lead chromate, 3% to 25% lead sulphocyanate, 2% to 30% zirconium and up to 35% ground glass. 5

3. A non-corrosive priming mixture comprising a combustion initiating agent, nitrates and chromates as oxidizing agents, and zirconium as a 10 fuel.

4. A non-corrosive priming mixture comprising a combustion initiating agent, nitrates and chromates as oxidizing agents, and powdered metallic zirconium and lead sulphocyanate as a fuel. 15

GEORGE H. JACOBS.
